UNITED STATES PATENT OFFICE

NATHANIEL S. REEDER, OF NEW YORK, N. Y., ASSIGNOR TO PRESSED STEEL CAR COMPANY, OF PITTSBURGH, PENNSYLVANIA, A CORPORATION OF NEW JERSEY

DUMP CAR

Application filed April 9, 1929. Serial No. 353,704.

An object of my invention is to provide a dump car with a mechanism for automatically and selectively limiting the opening of the discharging door as the body is tilted 5 and returning said door to a closed position as the body is righted.

Another object of my invention is to provide transversely movable arms at each side of the underframe of a dump car for engaging with the opening door as the body is tilted to limit the opening thereof and to return the door to a closed position, by causing the door to rotate about its hinges as the body is righted.

In dump cars of the type illustrated in the drawings, the door operating mechanism is independent of the door locking mechanism but perform their separate functions simultaneously with the dumping and righting movements of the car body. The door locking mechanism shown in the drawing forms no part of my invention but is merely illustrative of a preferred form of locking mechanism. The type of car shown in the drawings is known as the rotary trunnion dump car in which the body is supported directly on the underframe and rotates about the underframe during the first part of the dumping movement until trunnions mounted 20 on the sides of the body engage with the underframe after which the trunnions form pivots about which the body turns in completing the dumping movement. However, the form of door operating mechanism shown can be used equally as well with a body mounted on trunnions at each side of the underframe and tilting about these trunnions during the entire dumping movement. For the same reasons there has not been 25 shown a mechanism for tilting the body but any of the types well known to the prior art may be used such as pressure operated tilting cylinders mounted on the car underframe or the body may be tilted by any other mechanical means or by manual effort.

Referring now to the drawings, Fig. 1 is a transverse section through a dump car showing the body in load carrying position and the door operating mechanism; Fig. 2 30 is a transverse section through a dump car

showing the body in fully tilted position; Fig. 3 is a section through the underframe and door operating mechanism along the lines 3—3 of Fig. 2; Fig. 4 is a plan view of a portion of the underframe showing a 55 method of mounting the door operating mechanism on the underframe; Fig. 5 is a section through the underframe and door operating mechanism along the lines 5—5 of Fig. 4; Fig. 6 is a detail view of a portion 60 of the door operating mechanism; Fig. 7 is a section through the underframe and door operating mechanism taken along the lines 7—7 of Fig. 4.

Referring now in detail to the drawings, 65 reference character 1 indicates a dump car having a body 2 tiltably mounted on an underframe 3 and tilting to either side of the underframe in dumping. The walls of the body are formed of doors 4 hinged adjacent 70 the floor and opening downward to facilitate the discharging of the lading at the side towards which the body is dumping. For the purpose of illustrating the door operating mechanism, the sides of the body are shown 75 hinged and the end walls of the body have been omitted, but it is to be understood that the side walls may be made rigid and the end walls hinged so as to make an end dump car instead of a side dump car. In making 80 an end dump car the door operating mechanism instead of extending transversely of the underframe, as shown in the drawings, would extend longitudinally of the underframe and its operation and construction 85 would be the same as will later be described for a side dump car.

The essential elements of the door operating mechanism comprises the operating arms 5 pivotally mounted on the underframe 3 at 90 each side thereof and having a connecting member 6 joining the transversely opposite members 5 to control the movements of these members, as will later be explained. One end of the members 5 have suitably formed 95 portions 7 which engage with suitably formed portions of the body when the body is in horizontal position, as shown in Fig. 1 and through such engagement the body controls the movements of the door operating 100

mechanism as the body moves in dumping, as shown in Fig. 2. The member 5 at the end opposite to the end engaging with the body has mounted thereon a transversely moving arm 8 which has a portion 9 which engages with the opening door 4 to control the movement of such door as will become apparent as this description proceeds.

In order to confine the movements of the member 8 in a direction transversely of the body, the member 8 moves within a guide member 10 which has portions 11 and 12 thereof in engagement with the member 8. The portion 11 of the guide mechanism has a flat surface in engagement with the member 8 and the remainder of the member 11 is of arcate form and is movably mounted within the member 10 so as to permit the member 8 to rotate slightly within the guide member 10 in controlling the movement of the discharging door. The lower portion 12 of the guide member 10 is rigidly attached to the guide member, but has the portion in engagement with the member 8 of an arcate form for the same reason as above.

Since the door operating mechanism, as shown and described, is out of engagement with the doors of the body when the body is in load transporting position, it is necessary that an additional mechanism be provided for holding the doors in closed position. The mechanism as shown in the drawings automatically engages with the doors when the doors are returned to a closed position by the door operating mechanism simultaneously with the righting of the body after dumping and automatically releases the discharging door for opening as the body begins to tilt while maintaining the remaining door closed throughout the dumping movement.

When the body is in horizontal position, as shown in Fig. 1, and it is desired to discharge the contents thereof to the right side of the car as shown in Fig. 2, the following action takes place:—The body tilting mechanism, tilts the body towards the right hand side of the underframe and the door locking mechanism, simultaneously with the tilting action, releases the right hand door so that the door will open by gravity and the weight of the lading being discharged. The downward depending portion 13 of the door engages with the portion 9 of the transverse arm 8 of the door operating mechanism and remains in contact with this member throughout the entire dumping movement. The members 5 mounted on opposite sides of the underframe, and in engagement with the body when the body is horizontal, pass out of engagement with the body at the left side of the underframe as the left side of the body moves away from the underframe and the members 5 on the right side of the

body are moved downward towards the right side of the underframe by their engagement with the body and through their connection by means of the member 6 causing the mechanism at both sides of the body to move simultaneously. The arm 8 having the portion 9 thereof in engagement with the side door moves inwardly as the body tilts and the portion 9 in engagement with the depending portion 13 of the door follows the movement of that portion and as the body reaches its extreme dumping position limits the further opening of the door as is shown in Fig. 2.

It will be noted in Fig. 2 that the portion 9 is maintained in engagement with the door by the rotation of the door on its hinges and should the door strike an obstruction at the side of the track during any part of the dumping movement of the body which would prevent the further opening of the door, the body could continue dumping without injury to the door or the door operating mechanism.

When the body is returning to a horizontal position, the member 5 in engagement with the body moves with the body causing the member 8 to move transversely of the underframe and outward towards the open door. This outward movement of the member 8 in combination with its position above the portion 15 of the open door returns the door to a closed position before the body comes to rest on the underframe, by causing the door to rotate about its hinges as the body is righted. The member 8 on the left side of the body is also moved by its connection to the member 6 into a position to engage with the returning body. Since the door operating mechanism passes out of engagement with the doors a short time before the body comes to rest on the underframe, the door locking mechanism must of necessity engage with the doors and lock them into closed position as the body comes to rest on the underframe with the door operating mechanism in the position as shown in Fig. 1 of the drawing.

When the body is tilted towards the left side of the underframe, the action of the door operating mechanism is the same as previously described excepting that the members 5 on the left side of the underframe are the members which control the movement of the door operating mechanism and the door at the left side of the underframe opens by gravity as the body is tilted and is rotated into a closed position as the body is righted as previously described.

Neither the action nor construction of the door locking mechanism, or the portions of the car body and underframe about which the body tilts have been described in detail since these form no part of the present invention.

Throughout the description the inactive door operating mechanism has been described as moving simultaneously with the active mechanism, by means of the connecting member 6, but it is to be understood that the member 6 may be omitted and any other suitable means may be used for maintaining the inactive members 5 in position to engage with the returning body, without departing from the scope of my invention.

Having thus described my invention what I claim as new and desire to secure by Letters Patent is:

1. In a dump car, an underframe, a dump body tiltably mounted on said underframe in stable equilibrium, side doors for said body hinged adjacent the floor thereof, downward depending members on said doors and a door operating mechanism mounted on the underframe for selectively engaging with said body and depending door members to control the opening and closing of the side doors as the body moves in dumping, said mechanism comprising a member mounted on each side of the underframe and controlled by the body tilting toward said members, a member mounted on each side of said underframe adjacent the depending door members and movable into and out of engagement therewith, and means connecting the adjacent underframe mounted members.

2. In a dump car, an underframe, a dump body supported directly on said underframe in stable equilibrium, side doors for said body hinged adjacent the floor thereof, downward depending members on said door, a door operating mechanism mounted on the underframe for automatically and selectively controlling the opening and closing movements of the door at the side towards which the body is dumping, said mechanism comprising a member in engagement with the tilting body, a member movable transversely of the underframe into engagement with the depending member of the descending door and a connection between said members.

3. In a dump car, an underframe, a dump body tiltably mounted on said underframe in stable equilibrium, side doors for said body hinged adjacent the floor thereof and folding down in opening, downward depending members on said doors, a door operating mechanism for automatically controlling the opening and closing of the discharging door of the tilting body, said mechanism comprising a member mounted on the underframe and controlled by the tilting body, a member mounted on the underframe and movable transversely thereof to engage with the adjacent opening door and means connecting said members.

4. In a dump car, an underframe, a dump body tiltably mounted on said underframe in stable equilibrium, trunnions on said body

free of the underframe when the body is horizontal, said trunnions engaging with the underframe when the body is tilted and forming pivots about which the body turns in dumping, side doors for said body hinged adjacent the floor thereof, a member mounted on the underframe and actuated by the dumping car body, a member mounted on the underframe and movable transversely thereof to engage with the adjacent opening door and a connection between said members.

5. In a dump car, an underframe, a dump body mounted on said underframe in stable equilibrium, side doors for said body hinged adjacent the floor thereof, downward depending members on said doors, a member mounted on each side of the underframe adjacent said depending door member, a member mounted on each side of the underframe adjacent said first mentioned member and in engagement with the body, and means extending transversely of the underframe and in engagement with said members, said first mentioned members movable transversely of the underframe to engage with the adjacent depending member of the opening door as the body moves in dumping.

6. In a dump car, an underframe, a dump body supported directly on said underframe in stable equilibrium, side doors for said body hinged adjacent the floor thereof, downward depending members on said doors, a member mounted on each side of the underframe adjacent the depending door members, said member being movable transversely of the underframe to engage with the depending members of the adjacent opening door as the body is tilted, and means mounted on the underframe and having a selective engagement with the body to control the movement of said transversely mounted members.

7. In a dump car, an underframe, a dump body tiltably mounted on said underframe in stable equilibrium, side doors for said body hinged adjacent the floor thereof, downward depending members on said doors, a member mounted at each side of the underframe and movable transversely thereof, a member mounted on the underframe and having a selective engagement with the body, means connecting said members, a member mounted on said first mentioned member and movable longitudinally of the adjacent depending door member when the body tilts towards their respective sides.

8. In a dump car, an underframe, a dump body tiltably mounted on said underframe in stable equilibrium, side doors for said body hinged adjacent the floor thereof, downward depending members on said doors, a door operating mechanism on each side of the underframe adjacent the depend-

ing door members for controlling the opening and closing movements of said doors, means extending transversely of the under-frame and connecting said door operating mechanism, a member mounted on the underframe and having a selective engagement with the body for moving said door operating mechanism into engagement with the depending members of the adjacent opening door as the body tilts in dumping.
